UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,186,586.

Specification of Letters Patent. Patented June 13, 1916.

Application filed August 14, 1912. Serial No. 715,048.

To all whom it may concern:

Be it known that I, CHARLES J. KLEIN, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming 10 a part of this specification.

My invention relates to electric switches.

It has among its objects to provide an improved snap switch mechanism which is efficient in its action and may be readily 15 and cheaply manufactured.

A further object of my invention is to provide an improved electric flush switch adapted to make and break the circuit with a quick snap action when actuated in either 20 direction and which is of an improved rugged and unitary construction.

Other objects and advantages of my improved construction will hereinafter appear.

25 In order to clearly and fully disclose my invention I have illustrated one embodiment of the same in the accompanying drawings. My invention may, however, assume other forms.

30 Figure 1 shows a top plan view of an assembled center switch in its receptacle. Fig. 2 shows a longitudinal sectional view on line 2—2 of Fig. 1. Fig. 3 shows a transverse sectional view on line 3—3 of 35 Fig. 1. Fig. 4 shows a side elevation of the switch unit removed from the receptacle. Fig. 5 shows a longitudinal sectional view on line 5—5 of Fig. 1.

The switch mechanism includes two push 40 button operated cams 1 and 2 which are reciprocated in a frame 3 to reciprocate a movable contact carrying block 4 to make or break the circuit at stationary contacts 5 and 6 carried within a receptacle 7.

45 Both the cams 1 and 2 are formed of flat strips of sheet metal and are provided with active surfaces upon their adjacent edges. The active surface of the cam 1 is in the form of a hill having a sharp peak, while 50 the active surface of the cam 2 is inverted

with respect to the active surface of the cam 1 and is in the form of a valley, the sloping active surfaces of each cam member being substantially parallel with the corresponding surfaces upon the other. Push buttons 55 8 and 9 are fixed to extensions 10 and 11 upon the upper ends of these cam members. In order that the push button 9 may be raised when the push button 8 is depressed and vice versa, I connect the two 60 push buttons by means of a pivoted lever 12 pivoted at 13 to a depending portion 14 of the frame 3. The ends of this lever 12 are rounded and move in elongated transversely extending recesses 15 in the upper 65 ends of the cam members adjacent to the lower ends of the push buttons. As illustrated, suitable cut-away portions 16 are provided in the lower ends of the push buttons to permit the free movement of this 70 lever.

The movable contact block 4 is formed of insulation and is carried between the cams 1 and 2 and reciprocated by the same upon a pair of vertical spindles 17 and 18 located 75 upon the opposite sides of the frame 3 as shown in Fig. 3. As illustrated, these spindles extend through vertically extending metallic sleeves 19 carried by the block 4. A coiled spring 20 is housed in a horizontally extending metallic sleeve 21 located centrally within the member 4, and having its ends extending into recesses 22 in the ends of the same. This spring tends to normally press a pair of balls 23, 24 to their 80 outermost position in the vertically slotted ends 25 of the sleeve, wherein they engage with the active surface of the cams 1 and 2. As the push buttons are reciprocated, the balls 23 and 24 are pushed inward by the 85 movement of the cam members through the slotted ends of the sleeve. This compresses the spring 20. When the peak of the cam 1 is forced past the ball 23, the pressure upon the spring 20 is suddenly released and 90 the movable contact block is actuated with a quick snap action, the balls 23 and 24 traveling over the oppositely located active surfaces of the cams. In a preferred form 95 suitable extensions 26 are provided at the 100

2
ends of the active surfaces of the cams in order to limit the travel of the balls thereon. It is to be noted that the ball 23 travels entirely over the active surface of the cam 1, 5 while the ball 24 travels alternately back and forth over a half of the active surface of the cam 2, returning at the end of each operation to the position shown in Fig. 2. Obviously, upon the alternate reciprocation 10 of the push buttons the block 4 is alternately reciprocated in opposite directions. The movable contacts for the switch mechanism are carried upon the corners of this block 4. As illustrated, these contacts are formed of 15 a single piece of stamped metal and are insulated from each other by spacing the same apart as shown in Figs. 1 and 4. Each of the same is provided with a plurality of vertically extending contact surfaces 27, 28 20 which extend at right angles with respect to each other, and are bent down over the sides of the block as shown in Fig. 1. Obviously, these contacts may be attached to the insulating block 4 by any suitable means, as by 25 screws 29.

The switch mechanism is mounted in the frame 3 in such a manner that it constitutes with the frame a removable unit. The frame with the switch mechanism in position therein is shown in Fig. 4. This frame includes a horizontally extending top plate 3 and a substantially U-shaped member 30 attached to the bottom thereof. Both of these members are formed of stamped metal. The plate 3 is provided with openings through which the push buttons are reciprocated and at its ends is provided with openings through which the means for attaching it to a face plate and the base 7 are passed. The U-shaped member 30 is provided with a longitudinally extending slot 31 in its bottom. The lower ends of the spindles 17 and 18 are seated on opposite sides of this slot and extend between the member 30 and the top plate 3 to which they are likewise fixed. As illustrated in Fig. 2, the inner ends of the cam members move through the ends of the slot 31 and are provided with shoulders 32 which engage with the upper surface of the member 30 to limit the movement of the push buttons. In order to guide the cam members, suitable struck-in portions 33 are formed in the sides of the U-shaped member 30.

The receptacle 7 is formed of insulating material and is provided with an open top through which the switch unit is inserted. The frame 3 is attached to the receptacle 7 by means of screws 34 which extend through suitable vertically extending recesses 35 in 60 the ends of the receptacle and are received in threaded openings 36 in the ends of the frame 3. In a double pole switch such as illustrated, a plurality of sets of stationary contacts are carried upon each side of the

receptacle in a position to be engaged by the 65 contacts 27 and 28 on the contact block 4. A set of contacts 5 is provided at each corner of the receptacle. These contacts are resilient and attached to the bottom of the receptacle by means of screws 37, which in 70 turn connect them to vertically extending terminal posts 38 carrying binding screws 39. The lower ends of the terminal posts are provided with extensions 40 which are secured to the bottom of the receptacle by 75 means of screws 41. It is to be noted that each of the contacts 5 is divided into two resilient strips in order to increase its resiliency and make a better contact, and that the upper ends of the contacts constituting 80 the contact surfaces, are bent substantially at right angles to the body of the same, being provided with flared tips as shown. The contacts 6 are likewise resilient and arranged in pairs, being carried at the sides 85 of the receptacle at right angles to the contacts 5. These contacts are connected by integral metallic strips 42 as shown in Fig. 5, and are secured to the bottom of the receptacle by means of screws 43. As illustrated 90 in Fig. 1, the contacts 5 are adapted to engage the contacts 27 upon the movable contact block, while the contacts 6 are adapted to engage the contacts 28 carried thereon.

Obviously, when the switch mechanism is 95 in position within the base, a suitable face plate 44 may be placed in position upon the device as in the usual manner. It is to be noted that when it is desired to remove the entire switch mechanism, it is only necessary 100 to remove the screws 34, whereupon the entire operating mechanism may be withdrawn. It is further to be noted that the push buttons are positively driven so that the switch is always in position to be operated. The limits of travel of the block 4 are established by the engagement of the same 105 with the U-shaped member 30 when moved in one direction and by the engagement of the upper ends of the sleeves 17 and 18 with the top plate 3 of the frame when moved in the opposite direction. As heretofore indicated, the limits of travel of the cam members and push buttons are established by the engagement of the stops 32 with the bottom 110 plate 30. Further, the provision of the stops 36 upon the cam members serves to provide an additional balancing element for the parts. In order to permit the free movement of the cam members 1 and 2, the bottom 115 of the receptacle 7 is recessed at 45. Further, if desired, a suitable cushioning member 46, as, for instance, a leather strip, may be placed upon the bottom of the base or receptacle to cut down the vibration, etc., 120 upon reciprocation of the contact carrying member.

Assuming that electrical connections are

made to the binding screws 39 and that the movable contact block 4 is in the up or circuit closing position shown in Fig. 4, current flows in a similar path through the contacts 5 on each side of the switch,—from the binding screws 39 through the terminal posts 38, the resilient contacts 5, from these contacts to the contacts 27 and the contacts 28, one-half of the contacts 6 through the conducting strips 42, the other portion of the contacts 6 to the other contacts 28, the other contacts 27, the other contacts 5 and the other terminal post 31 to the other binding screws 39. When the push button then in the up position, *i. e.*, the push button 9, is depressed, the circuit is broken at the contacts 5, 6 on each side of the switch upon the downward reciprocation of the block 4 and the contacts 27 and 28 carried thereby. Thus when the pushbuttons are reciprocated the circuit is made or broken simultaneously with a quick snap action at a plurality of points in such a manner as to divide up the arc and avoid injurious sparking. While I have described one form of my invention in order to fully and clearly disclose the same, I do not restrict myself to the construction herein shown for purposes of illustration since this construction may be modified without departing from the spirit of my invention.

What I claim as new and desire to secure by Letters Patent of the United States is:

1. In an electric switch, in combination, cams comprising a pair of relatively and oppositely reciprocable rigid plates, one having a concave active surface and the other having a convex active surface, push-buttons fixed to the ends of said plates, and a contact-carrying member in resilient operative engagement with said cams and movable thereby in selective directions.
2. In an electric switch, in combination, reciprocable cams comprising flat plates having active surfaces on their adjacent edges, one of said active surfaces being concave and the other convex, push-buttons rigidly attached to the ends of said plates, a contact-carrying member therebetween, and means carried by said member resiliently engaging said active surfaces for imparting a snap movement to said member upon operation of said push-buttons and in a direction governed by the direction of movement of said concave cam.
3. In an electric switch, in combination, a plurality of reciprocable unyielding cams, one of the same having a concave active surface and another thereof having a convex active surface, a contact-carrying member interposed between said cams and reciprocable in a path parallel thereto, spring-pressed means carried by said member at right angles to its direction of reciprocation and resiliently bearing upon said cams, and
4. In combination, a unitary frame including a top plate and a U-shaped member fixed thereto, a snap switch mechanism movable in said frame and having a pair of operating cams movable through said top plate and limited by engagement with said U-shaped member, and a lever pivoted to said frame and acting to raise one of said operating members when the other is depressed. 70
5. In combination, a frame including a top plate and a U-shaped member fixed thereto, said U-shaped member having a slot 80 in its bottom, a plurality of cams movable through said top and bottom plates, said cams being guided and limited in their movement by engagement with portions of said U-shaped member, a spindle carried 85 by said U-shaped member, and a contact carrying member reciprocable on said spindle upon movement of either of said cams.
6. In combination, a frame including a top plate and a depending U-shaped member fixed thereto, a pair of reciprocable cams movable through said top plate and guided and limited in their movement by engagement with said U-shaped member, a pair of spindles carried upon said U-shaped 90 member and extending between the same and said top plate, a contact carrying member reciprocable on said spindles upon movement of either of said cams, and means carried by said frame for returning one of 95 said cams to its initial position when the other is operated.
7. In an electric flush switch, in combination, a reciprocable operated member having associated contacts, a pair of push button operating members therefor interlocked to reciprocate in opposite directions, means to receive and store energy upon movement of said push buttons for imparting an accelerated circuit-changing movement to 100 said operated member, a single cam on one of said push buttons engaging said operated member for governing the direction of accelerated movement thereof, and a single cam on the other of said push buttons for 105 temporarily restraining said operated member against movement, said cams co-operating during restraint of said operated member to effect a storage of energy in said means.
8. In an electric flush switch, in combination, a reciprocable operated member having associated contacts, a pair of push button operating members therefor disposed 110 on opposite sides thereof and interlocked to reciprocate in opposite directions, means associated with said operating members to receive and store energy for imparting an accelerated circuit changing movement to 115 said operated member, a single concave cam 120

on one of said push buttons and a single convex cam on the other engaging said operated member for temporarily restraining the same against movement, for effecting a storage of energy in said means during said restraint, and for timing the expenditure of such energy to move said operated member in selective directions.

In witness whereof, I have hereunto subscribed my name in the presence of two witnesses.

CHARLES J. KLEIN.
